(57) **CLAIM**

The ornamental design for a surgical instrument handle, as shown and described.

DESCRIPTION

FIG. 1 is a front and left side perspective view of a surgical instrument handle in accordance with the present design;

FIG. 2 is a top and left-side perspective view of the surgical instrument handle of FIG. 1;

FIG. 3 is a top plan view of the surgical instrument handle of FIG. 1;

FIG. 4 is a bottom plan view of the surgical instrument handle of FIG. 1;

FIG. 5 is a front elevation view of the surgical instrument handle of FIG. 1;

FIG. 6 is a rear elevation view of the surgical instrument handle of FIG. 1; and,

FIG. 7 is a right-side elevation view of the surgical instrument handle of FIG. 1, a left-side elevation view being a mirror image of FIG. 7.

The broken lines showing portions of the surgical instrument handle are included for the purpose of illustrating environmental structure and form no part of the claimed design.
